US00D971071S

(12) **United States Design Patent** (10) **Patent No.:** **US D971,071 S**
(45) **Date of Patent:** **** Nov. 29, 2022**

(54) **ARTIFICIAL PLANT**

(71) Applicant: **Henan Nanhua Qianmu Biotechnology Co., Ltd.**, Zhengzhou (CN)

(72) Inventor: **Xiaoli Li**, Zhengzhou (CN)

(73) Assignee: **Henan Nanhua Qianmu Biotechnology Co., Ltd.**, Zhengzhou (CN)

(**) Term: **15 Years**

(21) Appl. No.: **29/797,827**

(22) Filed: **Jul. 2, 2021**

(51) LOC (13) Cl. **11-04**

(52) U.S. Cl.

USPC **D11/117; D11/119**

(58) **Field of Classification Search**
